UNITED STATES PATENT OFFICE.

JOHN T. KELLY, OF NEW YORK, N. Y., ASSIGNOR OF ONE-HALF TO GEORGE M. JONES, OF PITTSBURG, PENNSYLVANIA.

DESIGN FOR A COUPLING MEMBER FOR RADIATOR-VALVES.

SPECIFICATION forming part of Design No. 33,260, dated September 25, 1900.

Application filed March 28, 1900. Serial No. 10,560. Term of patent 14 years.

To all whom it may concern:

Be it known that I, JOHN T. KELLY, a resident of New York, (Brooklyn,) in the county of Kings and State of New York, have invented and produced a new and useful Design for a Coupling Member for Radiator-Valves; and I do hereby declare the following to be a full, clear, and exact description thereof.

My design relates to a coupling member for radiator-valves, the characteristic feature of which is the rectangular box like form of the body having its lower end rounded and provided with an ornamental cap.

In the accompanying drawings, illustrating my design, Figure 1 is a perspective view of the coupling member, and Fig. 2 is a side view of the same.

The coupling member 1 has substantially the form of a rectangular box having its corners cut away, as shown at 2, and having the threaded opening 3 in one of the side faces

thereof. Below this threaded opening the corners of the body are rounded off to form the circular portion 4, below which is the ornamental cap 5, and at the top of the body is 25 the projecting circular flange 6 and a projecting cone 7, surrounding the opening 8 in the top of said member. The rectangular form of the body having its lower end rounded and provided with an ornamental cap forms a 30 coupling member neat and pleasing in appearance.

What I claim is—

The design for a coupling member for radiator-valves herein shown and described. 35

In testimony whereof I, the said JOHN T. KELLY, have hereunto set my hand.

JNO. T. KELLY.
